Atty.

UNITED STATES PATENT OFFICE.

FRANCIS H. HARVEY, OF BATON ROUGE, LOUISIANA, ASSIGNOR OF ONE-HALF TO JOHN S. PEARCE, OF SAME PLACE.

NUT-LOCK.

SPECIFICATION forming part of Letters Patent No. 393,303, dated November 20, 1888.

Application filed August 4, 1888. Serial No. 281,925. (No model.)

To all whom it may concern:

Be it known that I, FRANCIS H. HARVEY, of Baton Rouge, in the parish of East Baton Rouge and State of Louisiana, have invented 5 a new and useful Improvement in Nut-Locks; and I do hereby declare that the following is a full, clear, and exact description of the same.

My invention is an improved device for locking nuts upon bolts to prevent their loosening, 10 and is designed particularly for use upon railroads where the nuts securing the fish-plates to the rails are likely to become loose owing to the jarring caused by passing trains.

Many devices have been heretofore patented 15 for the purpose above noted, but all are more or less objectionable, owing to cost of manufacture and lack of efficiency in operation; but my invention has for its object to provide a device which can be manufactured very cheaply, 20 and which shall be very effective in accomplishing the desired result.

My invention therefore consists of the various details of construction whereby I am enabled to carry out my invention, all as herein- 25 after fully described, and specifically claimed.

In the accompanying drawings, Figure 1 is a perspective view of two adjoining rails with my improved nut-lock in place. Fig. 2 is a plan view of the locking device before it is 30 placed in position.

In the drawings, the rails are represented at A A, connected by fish-plates B, and the bolts joining the plates to the rails are shown at a and the nuts for the same at b. My improved 35 locking device is represented at C. It is stamped out of sheet metal in the form shown in Fig. 2, with extensions on all four sides, the longitudinal portions being marked c c and the

transverse portions d d. The portions c c are in width about equal to that of the fish-plate, 40 and have holes e e at suitable distances apart, through which the bolts a pass. One of the transverse extensions d has its end contracted to form a tongue, as f, and this tongue is adapted to pass through a slit, g, cut on the other trans- 45 verse extension d when the parts are folded together, and thus by bending back the tongue upon itself the parts will be securely fastened together. After screwing on the nuts and before folding the parts together, I place upon 50 the sheet-metal locking device a block of metal or other suitable material, h, just about equal in length to the space between two nuts, and this block acts to prevent the nuts from turning, and is itself prevented from dropping off 55 by means of the interlocking of the parts d d.

It will be obvious that the locking-plate may be of any length, it being only necessary that between any two bolt-holes or every other pair of bolt-holes the transverse extensions should 60 be made in order to hold the block h in place to prevent the nuts from turning.

I claim as my invention—

A device for locking nuts, consisting of the plate C, fitting over the bolts, a block, h, inter- 65 posed between the nuts, and the interlocking portions d d—one above and one below on the plate C—for embracing said block and holding it in position, substantially as described.

In testimony whereof I have signed my name 70 to this specification in the presence of two subscribing witnesses.

FRANCIS H. HARVEY.

Witnesses:

JOHN S. PEARCE,
W. H. GOODALE.
